UNITED STATES PATENT OFFICE.

JOSEPH P. SANDER, OF SPOKANE, WASHINGTON, ASSIGNOR TO SPOKANE MAIL EQUIPMENT COMPANY, OF SPOKANE, WASHINGTON.

MAIL-BAG-CATCHING DEVICE.

1,174,291.

Specification of Letters Patent.

Patented Mar. 7, 1916.

Application filed September 2, 1914. Serial No. 859,865.

To all whom it may concern:

Be it known that I, JOSEPH P. SANDER, a citizen of the United States, residing at Spokane, in the county of Spokane and 5 State of Washington, have invented certain new and useful Improvements in Mail-Bag-Catching Devices, of which the following is a specification.

This invention relates to improvements in 10 mail catching and delivering mechanism for transferring bags of mail from a station to a car, and vice versa.

The invention has to do more particularly 15 with that type of device employing a fork for catching a portion of the bag, a retaining device being mounted on the fork for retaining the bag after the same has been caught.

My invention consists in a novel retainer 20 pivotally mounted on the catching fork and having an abutment portion for actuation by a caught bag to swing the retainer on its pivot and shift a hook-shaped portion of the retainer into the path of the bag so 25 that stress imposed by rebound engagement of the bag against and into said hook-shaped portion will, because of the novel formation of the hook-shaped end, serve to secure the retainer in a bag holding position. 30 Because of the construction, I am able to entirely avoid the use of springs and other locking devices which have heretofore been necessary in order to secure the retainer in a bag holding position.

The invention comprises further novel 35 features and objects which will be more fully described in connection with the accompanying drawings and which will be more particularly pointed out in and by the appended claim.

In the drawings:—Figure 1 is a view in 40 side elevation of a station and a portion of a car and illustrating the application thereto of one form of my invention; Fig. 2 is a horizontal sectional view of a portion of the car, showing the station in plan; Fig. 3 is an enlarged sectional view of a novel form 45 of mounting shaft for the catching arms; Fig. 4 is a perspective view of an arm holder; Fig. 5 is a fragmentary end view of one portion of a catching arm; Fig. 6 is an enlarged view of the forked end of the 50 catching arm showing the retainer thereof in one position; and Fig. 7 is a view simi-

lar to Fig. 6 showing the retainer in another 55 position.

Like characters of reference designate similar parts throughout the different figures of the drawings.

As illustrated, 1 designates a car which is 60 indicated as traveling in the direction of the arrow, and 2 designates a station. On the station 2 is a bag holding means A, for holding a bag to be caught by a passing train, the station also being provided with 65 a bag catching device B, for catching a bag from a train passing in one direction, and a similar device C, for catching a bag from a train passing in an opposite direction.

First referring to the catching and delivering means upon the car, 3 designates a mounting shaft provided with a threaded journal 4 which has threaded engagement with a bearing 5. The upper end of said shaft 3 is mounted in a car bearing 6 and 75 the purpose of the threaded engagement is to axially shift the shaft 3 during impact rotation thereof. On the shaft 3 are adjustably mounted two arm holders 7 and 8 which are provided with hubs 9 and 10 adapted to 80 be adjustably fixed on shaft 3 by set screws 11 and 12. A spring 13 is interposed between hub 9 and bearing 6 so that axial movement of shaft 3 will compress the spring, causing the latter to resist impact 85 rotation of the shaft. This feature is more fully described, and is claimed, in my co-pending application filed Sept. 2, 1914, Serial Number 859,866. Bag catching arms 90 14 and 15 are mounted in said holders 7 and 8 respectively, and as they are of identical construction, only one need be described in detail. The holder 7 is provided with a socket 16 having offset portions 17 shaped to correspond to the cross section of arm 95 14. Said arm is provided with ribs or feathers 18 fitting in said offset portions 17 to securely anchor the arm therein. The arm 14 is provided with a bore 19 and the holder 7 is provided with a bore 20 into which a 100 locking pin 21 may be inserted to lock the arm 14 in position. The outer end of arm 14 is provided with a catching fork having diverging terminals 22 and a throat portion 23.

The device of my invention is adapted for 105 use in connection with a bag having oppositely extending transfer lines or chains 24

and 25, the terminal ends of which are provided with heads 26 and 27, it being one of the principal objects of the invention to grasp the bag at both ends thereof.

I will now describe a novel form of retainer whereby the transfer devices of the bag will be securely held against displacement after being caught by the catching forks. I prefer to provide each fork with a retaining device and as they are identical in structure and operation, only one need be described in detail.

Referring more particularly to Figs. 6 and 7 28 designates a half ring or goose neck retainer which is shown pivotally mounted at 29 to the catching fork adjacent to the crotch 30 of the latter. When the retainer is in the position shown in Fig. 6, its impact terminal 31 will lie in the path of the transfer device 25, and as the latter advances relatively to the fork the transfer device 25 will strike the impact terminal 31 and shift the retainer from the position shown in Fig. 6 to the position shown in Fig. 7. In the latter position, the neck 32 will extend across the throat 23 of the fork so as to prevent rebound of the device 25 outwardly in the fork. To more effectively perform this function, I slightly hook the remaining terminal of the retainer 28, as indicated at 33, which formation renders the device more effective and prevents accidental release. It will be seen that the pivot 29 is not only disposed eccentrically with respect to the half ring retainer 28, but it is also disposed at one side of the longitudinal axis of the throat 23 thereby providing ample leverage and swing to insure movement of the terminal 33 across the throat 23. By reference to Fig. 7, it will be seen that any rebounding tendency of the device 25 to move outwardly, will serve to hold the retainer against movement from a locking position.

The usual action of the device 25 against terminal 31, will be to shift the retainer into the dotted line position shown in Fig. 7, the rebound of 25 causing the retainer to thereafter move into the position shown in full lines, in Fig. 7. Thus, the device 25, first strikes the terminal end 31, and thereafter, the interior of the retainer, at 34. When the retainer is in a normal retaining position, as shown in Fig. 7, there is enough play afforded to the device 25, to permit movement

thereof under swinging leash of the bag, so that the devices 25 are relieved from the strain to which they would be subjected if the devices were held against any movement in the forks. Further, and because of this peculiar shape of the retainer, if the device 25 is suddenly shifted to the right of Fig. 7, it will strike 34, and tend to more securely move the retainer across the throat of the fork so as always to block the device 25 as it shifts back to the left of Fig. 7.

The shafts of the station catchers, indicated at 35 and 36, are in all respects similar to shaft 3, and are provided with bearings 37-38 and 39-40, which operate to shift them axially, springs 41 and 42, functioning the same as spring 13. The forks of the station catchers will also be provided with retainers, similar to retainer 28.

It is believed that the novelty and utility of my invention will be fully understood from the foregoing description, and while I have herein shown and described one specific form of my invention, it will be understood that I do not wish to be limited thereto except for such limitations as the claim may import.

I claim:

In a mail bag catching device, a fork having a throat to receive a portion of a mail bag, and a half ring-shaped retainer pivoted to said fork at one side of said throat and nearer one end of said retainer than the other, thereby forming a relatively short and long end, the shorter end forming an impact terminal and lying near the crotch of said throat and in the path of an entering bag portion to swing said retainer on its pivot across said throat until an inner intermediate portion of the retainer hugs said bag portion closely against the crotch of said throat, the longer end of said retainer being hook-shaped to catch the bag portion on rebound thereof and prevent the longer hook-shaped end of said retainer from being shifted backwardly beyond and to one side of said throat, substantially as described.

In testimony whereof I affix my signature in presence of two witnesses.

JOSEPH P. SANDER.
